UNITED STATES PATENT OFFICE

2,508,209

KNITTING MACHINE AND METHOD

Roy C. Amidon, Reading, Pa., assignor to Vanity
Fair Mills, Inc., Reading, Pa., a corporation of
Pennsylvania

Application October 15, 1945, Serial No. 622,266

60 Claims. (Cl. 66—86)

1

My invention relates to machines for producing fabrics similar to the fabrics covered by my Patents No. 2,136,367, issued November 15, 1938; No. 2,155,385, issued April 25, 1939; No. 2,331,289, issued October 12, 1943; and No. 2,369,651, issued February 20, 1945; it further relates to machines of the tricot or fast warp type, such as those covered by my Patents No. 2,136,368, issued November 15, 1938; No. 2,155,386, issued April 25, 1939; No. 2,243,850, issued June 3, 1941; No. 2,313,725, issued March 10, 1943; and No. 2,336,455, issued December 14, 1943.

Heretofore it has been the common practice in designing tricot-type machines, to operate the needle bars through cam-operated levers, and such machines generally use latch or spring-beard needles, or needles having sliding tongues. In such machines, the swinging thread guides have almost universally been employed, and, furthermore, the needle bars, the sinker bars, and the thread guides have all been given motions which include substantial periods of dwell in their respective cycles of movements; for instance, the needles are required to dwell while the thread guides pass forwardly and backwardly to place the thread around the needle; also the thread guides have periods of dwell between their forward and backward swings.

In other machines for producing flat knit fabrics, eccentrics have been used to replace the cams which give movement to the needles, sinkers and thread guides, and in order to obtain the dwell periods necessary to the knitting process two eccentrics, one operating at twice the speed of the other, have been used, the eccentrics being operatively connected together by a cross-bar and the cross-bar being connected to the bars to which the needles, guides and sinkers are attached. Machines of the prior art using eccentric motions in whole or in part are disclosed, for examples, in Patents: No. 417,221 to Berry, December 17, 1889; No. 1,165,294 to Springthorpe, December 21, 1915; No. 1,623,603 to Springthorpe, April 5, 1927; No. 2,155,145 to Morton, April 18, 1939; No. 2,292,287 to Peel et al., August 4, 1942; and No. 2,339,153 to Cotterill, January 11, 1944.

The objects of my invention are:

1. To provide a machine wherein high speeds (900 R. P. M. and over) may be obtained;
2. To provide a machine in which vibration and shocks will be reduced to a minimum;
3. To provide a machine by means of which an almost infinite variety of fabrics, cloths, nets, etc., of an almost infinite variety of patterns can be knit;

2

4. To provide a machine in which the use of spring-beard needles, latch needles and longitudinally sliding tongues is eliminated;
5. To provide a machine in which the number of cam actions is reduced to a minimum;
6. To provide a machine in which the needles, tongues, and sinkers are in constant smooth motion without substantial periods of dwell;
7. To provide a machine in which the needle bar, the tongue bar and the sinker bar are all carried on a single rock shaft;
8. To provide a machine in which thread guides that are only movable back and forth in a direction to lay the thread across the needles are employed, which guides can be located with their eyes quite close to the path in which the sinkers move back and forth;
9. To provide a machine in which needles and tongues of the kind disclosed in my Patent No. 2,436,371, issued February 24, 1948.
10. To provide a machine in which the rock shaft, the needle bar, and the sinker bar are actuated by eccentrics through an adjustable system of levers and connecting rods;
11. To provide a machine in which the needles draw thread by engaging the threads with the back of the needle shanks on the up-strokes of the needles as the needles pass forward and upward through between the thread guides and hook the threads on the downward-rearward movement of the needles before the needle hooks enter the sinkers;
12. To provide a machine in which a specially designed thread let-off-take-up mechanism and a specially designed cloth take-up mechanism cooperate with one another and with the needles to keep the thread always under the desired tension from beam to cloth-take-up roll, and to operate both mechanisms with eccentrics.
13. To provide a machine in which a rock shaft carries bearings offset from the axis of the shaft, in which the needle-bar-carrying rods are reciprocal under the action of an eccentric or eccentrics and which bearings rock with the shaft, by virtue of which the needles may be made to travel in a predetermined path, part of which at least is a loop, during which the needles first draw and then hook the thread from the beam via the guides;
14. To provide a machine in which the tongue bar is provided with carrying rods that are slideable in bearings, the bearings being carried by and rockable with the rock shaft, and in which provision is made to move said bearings back and forth in a direction normal to the axes of said

bearings for the purpose of closing and opening the hooks of the needles while the tongue-bar is being reciprocated in time with the needle bar.

15. To provide a machine in which the rock shaft is operated by a double eccentric mechanism while the needle bar is moved to impart longitudinal motion to the needles by a single eccentric mechanism so that variations in the form and dimensions of the loop part of the path of movement of the needle hooks can be had through adjustment of the double eccentric mechanism alone.

16. To provide a machine in which the hook closing and opening movements may be imparted to the tongues at proper times by means of an eccentric mechanism.

17. To provide a machine of a simple yet rugged and compact structure, comparatively low in cost of manufacture, efficient in operation and inexpensive to maintain.

Other objects will in part be obvious and in part will be pointed out hereinafter.

To the attainment of the aforesaid objects and ends the invention also resides in those novel details of construction, combination and arrangement of parts all of which will be first fully described hereinafter and then be specifically pointed out in the appended claims, reference being had to the accompanying drawings in which—

Fig. 1 is a front elevational view of a portion of the left hand end of the machine, a frame-pipe being omitted.

Fig. 2 is a front elevational view similar to Fig. 1 of a portion of the machine at the end opposite that shown in Fig. 1.

Fig. 3 is an end view of the machine looking from left to right in Fig. 1.

Fig. 4 is an end view of the machine looking from right to left in Fig. 2.

Figs. 5—5A when joined on the lines *a—a* are an enlarged view looking from left to right in Fig. 2.

Fig. 6 is a detail section on the line 6—6 of Fig. 5.

Fig. 7 is a detail front elevation of a portion of the machine, looking from right to left in Fig. 5.

Fig. 8 is an enlarged detail cross section on the line 8—8 of Fig. 7.

Fig. 9 is a rear elevation of a portion of the structure shown in Fig. 8, looking from left to right in that figure.

Fig. 10 is a plan view of a portion of the mechanism shown in Fig. 5 looking down from line 10—10 in that figure.

Fig. 11 is a detail perspective view of one of the swivel bearings.

Fig. 12 is a detail vertical section on the line 12—12 of Fig. 10.

Fig. 13 is a detail top plan view of one of the rocking bearing units.

Fig. 14 is an end elevation of the same.

Fig. 15 is a front elevation of the same.

Fig. 16 is a detail plan view of one of the bell cranks and its slidable bearing block.

Fig. 17 is an enlarged detail front elevation of one of the tongue-bar sliding supports.

Fig. 18 is a side elevation of the same.

Fig. 19 is a detail plan view of a portion of the thread let-off mechanism.

Fig. 20 is a detail view of one of the let-off mechanism-operating rocker arms.

Fig. 21 is a detail of one of the shaft-rocking arms.

Fig. 22 is a detail section on the line 22—22 of Fig. 3.

Fig. 23 is a section on the line 23—23 of Fig. 22. 75

Fig. 24 is a detail longitudinal section and part elevation hereinafter again referred to.

Figs. 25 to 33, inclusive, are diagrammatic views hereinafter specifically referred to.

Fig. 34 is an enlarged elevational view showing the eccentric mechanism for operating the lower thread let-off.

Fig. 35 is a similar view of the eccentric mechanism for operating the upper thread let-off.

Fig. 36 is a section on the line 36—36 of Fig. 35.

Fig. 37 is a detail elevational view of one of the pivot studs.

Fig. 38 is a detail elevational view of another pivot stud.

Fig. 39 is a detail view of a portion of one of the slotted adjustable plates of the thread let-off mechanism.

Fig. 40 is a view similar to Fig. 5 illustrating another embodiment of my invention.

Fig. 41 is a detail diagrammatic view of the double eccentric mechanism for operating the lower or rear thread let-off.

Fig. 42 is a detail, diagrammatic view of the double eccentric mechanism for operating the upper or front thread let-off.

Fig. 43 is a detail, diagrammatic view of the double eccentric mechanism for moving the tongues laterally to close the needle hook beard.

Fig. 44 is a detail, diagrammatic view of the double eccentric mechanism for rocking the main rock shaft.

Fig. 45 is a detail, diagrammatic view of the single eccentric mechanism for advancing and retracting the sinker.

Fig. 46 is a detail, diagrammatic view of the single eccentric mechanism for moving the needle and the tongue longitudinally or in an up and down motion.

Figs. 47 to 55 inclusive are diagrammatic views hereinafter specifically referred to.

Fig. 56 is a diagrammatic view of a modification hereinafter specifically referred to.

In the drawings in which like numerals and letters of reference indicate like parts in all the figures, 1 to 9, inclusive, indicate the various points along the path *P* which the needles and tongues take in going through the knitting cycle as best indicated in Figs. 25 to 33 inclusive to which further reference will be made hereinafter.

The machine of my invention includes end frames 10 which are connected by longitudinal pipes 11 and which have bearings 12 for the beams 225 and 226 respectively. Journalled in suitable bearings in the end frames 10 is a main eccentric shaft 13 and a second eccentric shaft 14. The shaft 14 is driven at twice the speed as that of the shaft 13 in any suitable way as for example a sprocket and chain drive 15, 16, 17, see Fig. 3. The main eccentric shaft has two worms, one, 18, on one end of the shaft and the other, 19, on the other end of the shaft (see Figs. 1 to 4, inclusive).

Carried on cross bars 20 of the end frames is a longitudinally disposed support 21 on which the fixed tubular upright guide bearings are mounted as will later be more fully explained.

Journalled in suitable bearings in the end frames 10 is a main rock-shaft 22 on which is firmly secured an arm 23. A tubular upright guide bearing 24 is mounted on the support 21. This bearing 24 receives a plunger or tubular shank 26 that depends from a fulcrum-head 25 that is pivoted to the cross-bar 27. One end of the cross-bar 27 is pivoted, at 32, to the eccentric yoke arm or strap 28 for the eccentric 30, while

the other end of the same is pivoted, at 33, to the eccentric yoke arm or strap 29 of an eccentric 31 on the shaft 14. A connecting rod 35 is adjustably pivoted to the arm 23 and to the pivot 34 that connects the head 25 and cross-bar 27 (see Figs. 1, 2 and 3). This mechanism imparts the required rocking motion to the main rock-shaft 22. The bearing 24 is held in place by cap screws 36. It should of course be understood that at least two arms 23 and eccentric operating devices above described are used in the machine, see Figs. 1 and 2.

The eccentric mechanism for operating the lower (back) thread let-off is best shown in Figs. 5 and 34, and as shown in Figs. 1 and 2, at least two sets of operating mechanisms are used, the two being alike. These mechanisms each comprise a fixed tubular upright bearing 37 secured by cap screws 36 to the support 21. A tubular shank or plunger 38 works in the bearing 37 and is attached to a fulcrum head 44. A cross-bar 39 is pivoted at 45 to the head 44 and has one of its ends pivoted at 46 to the eccentric yoke 40 for the eccentric 42 that is located on the main eccentric shaft 13. The other end of the cross-bar 39 is pivoted at 47 to the eccentric yoke 41 for the eccentric 43 that is mounted on the shaft 14. Slotted arms 49 are mounted to turn on the rock-shaft 22 and are connected to the pivots 45 of the respective heads 44 by links 48. The arm 49 also has a slotted arm 49^a to which the connecting rod 50 from the sliding carriage 214, shown in Fig. 5, connects.

The eccentric mechanism which operates the upper (front) thread let-off is substantially the same as that which operates the lower (back) thread let-off. This mechanism is shown in detail in Fig. 35 to which reference is now made and in which it will be seen that a tubular upright bearing 61 is secured to the support 21 and receives the shank or plunger 60 of the fulcrum head 59. A cross-bar 55 is pivoted at 58 to the head 59 and has one of its ends pivoted at 56 to the eccentric yoke 53 for the eccentric 51 that is mounted on the shaft 13. The other end of the cross-bar is pivoted at 57 to the eccentric yoke 54 for the eccentric 52 that is mounted on the shaft 14. A link 62 is pivoted at 58 and has its upper end adjustably pivoted to a slotted arm 63 that is rotatably mounted on the shaft 22. The arm 63 also has a slotted branch 64 to which is adjustably pivoted the connecting rod 65 that is also pivoted at 215 to the sliding carriage 214 of the upper thread let-off.

The needle bar raising and lowering eccentric mechanism is best shown in Figs. 1, 2, 5, 7, and 8, by reference to which it will be seen that eccentrics 66 on shaft 13 have their yokes 67 pivoted to bifurcated coupling members 68 that are secured at 89 to the needle bar raising and lowering hollow rod or shaft 71. Each rod works in a bearing 70 carried by an arm 69 that is secured on the shaft 22. The shaft 71 has a head 72 on its upper end. This head has an integral bearing member 73 and a detachable bearing member 74 secured to it by cap screws 72^x and spaced apart as best shown in Fig. 8. A needle-bar 75 is secured to the head 72 by cap screws 88 and has bearing holes 76 that align with the bearing members 73 and 74.

The tongue-bar 83 lies between the bearing members 73 and 74 and is carried on slide rods 84 that are operatively held one in each pair of bearing members. Each rod 84 has a recess 86 in which the tongue bar 83 sets. Each rod 84

has lugs 85 to which the tongue bar 83 is attached by cap screws 87.

A hollow guide rod 80 is formed integrally with a cap plate 79 and a hollow guide rod 81, the rods 80, 81 lying at right angles to one another (Figs. 17, 18). The needle bar 75 has bearings 75^x in which the rods 81 lie (Fig. 7) and the plates 79 are secured to the tongue bar 83 by cap screws 82.

Each guide rod 80 slides in a guide bearing 71 which is formed with an arm 78 that slides in the transverse slideway 96 of a rocking-bearing unit.

The construction of the rocking-bearing unit is best shown in Figs. 13 to 15 inclusive by reference to which it will be seen that on the sleeve portion 90 of the unit is a rearwardly projecting bracket 91 that carries, at two different levels, upper and lower threaded sockets 92, 93 respectively. The unit also includes two slide-rod bearings 94, 95 parallel to one another and to the axis of the sleeve portion 90. The unit further includes the transverse slideway 96, above referred to, and a transverse tubular bearing 98. A vertical web 97 supports the bearings 94, 95, 98 and in part the slideway 96. The sleeve 90 is made fast on the shaft 22 to turn with it.

A bearing spindle 99 (Figs. 5 and 37) is threaded into the socket 92 while a similar bearing spindle 100 is threaded into socket 93.

30 The bearing spindles 99 and 100 are of similar construction to the bearing spindle 107 carried by the sinker bar 101. The spindle bearing 107 includes a threaded end 108 and a threaded recess 109 to receive a cap screw 111 for holding a cap 110 in place (Fig. 38).

The sinker bar 101 is supported by hollow rods 102 that are slidably mounted in the bearings 98 (Fig. 12). The rods 102 have threaded ends 104 to receive attaching brackets 103 held in place by washers and nuts 105. The sinker bar 101 is secured to these brackets 103 by cap screws 106 (Figs. 7 and 12).

A bell crank lever 114 is pivoted to each spindle 99 and is held thereon by a cap 112 and cap screw 113.

Levers 114 have slotted arms 115 in the slots of which are held slide blocks 116 having bearing holes to receive the studs 118 of swivel blocks 117 that are attached to the sinker-bar-operating rod 119. The lever 114 has an arm to which one end of a connecting rod 120 is pivoted, the other end of the rod 120 is pivoted to the bearing spindle 107.

By imparting longitudinal movement to rod 55 119, the sinker bar is moved to advance and retract the sinker as desired, as will later more fully appear.

A bell crank lever 121 (see Fig. 16) is pivoted on the spindle 100 and has a slotted arm 122 in 60 which a slide block 123 is held by an angle plate 127. A swivel bearing block 124 is secured to the tongue operating rod 126 and has a stud 125 which lies in a bearing hole in slide block 123. The slide arm 78 which carries the bearing 77 65 is pivoted to the other arm of lever 121. Therefore as rod 126 is moved back and forth the tongues 165 will be moved from and toward the needle shanks to close and open, respectively, the beard-hooks 164 of the needles 162.

70 The mechanisms for operating the rods 119 and 126 are substantially of the same construction. By reference now to Figs. 2 and 4 it will be seen that the rod 126 has a cap 128 that is slotted to receive one end of an adjustable connecting rod, the two parts 129 and 130 of which

are secured together by clamping screws 131 and adjusted by an adjusting screw 132. The rod part 129 is pivoted to the cap 128 as at 129^a while the rod part 130 is pivoted at 130^a to the upper arm 135 of a cam actuated lever 135, 138, which lever is mounted on a transverse shaft 136 held in suitable bearings 137^a carried by brackets 137 suitably secured at 137^b to one end frame 10. The lever arm 138 is bifurcated, each fork carrying a truck or cam-engaging roller 139, 140 to engage the cam 141 which controls the action of rod 126. A two-part push rod 133, with turnbuckle joint 134 has its end held in concavities 129^b, 130^b in the cap 128 and lever 135 respectively.

The rod 119 also has a slotted cap 142 (see Fig. 4) to which one end 143 of a second adjustable connecting rod is pivoted as at 129^a (Fig. 4). The other end 144 of the connecting rod is pivoted at 144^a in a slot in a second lever 149, 151. The lever 149, 151 is mounted on a second transverse shaft 150 in suitable bearings 149^b in the brackets 131. The bifurcated parts of the lever 149, 151 also carry trucks or cam-engaging rollers 152, 153 to cooperate with the cams 154 on shaft 155.

A two-piece push rod 145 has a turnbuckle 146 and has its ends set in recesses 149^a in the lever 149. Clamping screws 148 secure the two parts of the connecting rod 143, 144 together and a screw 147 provides for adjustment.

The several trucks or rollers 139, 140, 152, 153 have adjustable bearings and adjusting screws 156 to take up wear.

A worm gear 157 on shaft 155 contacts the worm 18 on shaft 13 by virtue of which shaft 13 drives shaft 155 to operate the levers 135 and 149 properly.

Referring now particularly to Figs. 5 and 25 to 33 it will be seen that each sinker 158 includes blades having an upwardly, inwardly curved slot 160, a nib 159 and a hill or hump 161 as shown.

The needles 162 are mounted in leads 163 secured at 168 directly to the needle bar 75, while the ends 166 of the tongues 165 lie freely in sockets in leads 167 that are secured to the tongue bar 83 by cap screws 169 (see Fig. 8).

The sinkers 158 have their leads secured to the sinker bar 101 by cap screws 170.

Thread-guide-racking rods 171 and 172 are longitudinally slidably mounted in suitable bearings in the end or cross frames 10. These rods have spline portions 173 on which thread-guide carrying arms 174, 175 are mounted. The arms 174 and 175 respectively have secured to them the thread-guide bars 176, 177. The bars 176, 177 carry the thread guides 178, 179 respectively, as best shown in Figs. 1, 2 and 5.

The mechanisms for operating the rods 171, 172 are best shown in Figs. 1, 3 and 22 by reference to which it will be observed that each rod has a slotted cap on one end. The cap on rod 171 is numbered 180 and that on rod 172 is numbered 181. In suitable bearings on bracket frames 204, secured to the end frame 10 at the end of the machine opposite that having the frames 137, is a shaft 182 on which the rocking levers 183, 184 are pivoted. A pattern wheel shaft 185 is also mounted in suitable bearings in frame 204, and carries the pattern wheels 190, 191, 192, 193 best shown in Fig. 3. A third shaft 186 is mounted below the pattern wheel shaft 185 and is geared thereto by spur gears 187. A worm gear on shaft 185 meshes with the worm 18 on shaft 13 to effect operation of the pattern

wheel shaft. The lever 183 has trucks or rollers 193 to engage the pattern wheel 189 and the follower pattern wheel 190, while lever 184 has similar trucks or rollers 194 to engage the pattern wheel 191 and the follower pattern wheel 192.

Cams 195 (one for each lever 183) are carried on shaft 186 and are engaged by presser rollers 196 on rods 198 and held in engagement by springs 197.

Roller adjusting screws 199 are provided for maintaining contact between the rollers 193, 194 and their respective cams.

200 is an adjustable connecting rod between the cap 180 and the lever 183, and 201 is an extensible push rod, which rod 201 is also located between the cap 180 and lever 183.

A similar adjustable connecting rod 202 and extensible push rod 203 connect cap 181 with lever 184. These connecting rods and push rods, etc., are of the same kind as those, 133, 134, 144, 145, hereinbefore described.

The thread let-off and tensioning mechanism is best illustrated in Figs. 1, 2 and 5, by reference to which it will be seen that upper brackets 205 have grooved cuffs 206 to fit the splines 173 on racking rod 172, while a similar bracket 222 has its grooved cuffs 206 fitted on the splined parts of shaft 171. Each bracket 205 and 222 has a cylindrical bearing 207 socketed to receive a spring loaded eye-bolt 212, the eye-bolts carrying a rod 213 over which the threads from the beams are drawn. Each bracket 205, 222 also has a bearing 208 in which an eye-bolt 209 is mounted and is spring-pressed as at 210, the eye-bolts 209 carrying a rod 211 under which the thread is drawn.

Each bracket 205 has a slot in which a sliding carriage 214 is mounted. Each carriage 214 carries a stationary or fixed rod 218 to which 40 is attached a finger plate 219 under the edge or lip 220 of which the thread passes. An adjustable gauge plate 216 is attached at 224 to each bearing 208 and cooperates with the respective finger plate in the following manner: 45 namely, when carriage 214 rises a certain predetermined distance to let-off the thread between rods 213 and 211 the thread will engage the free edge 217 or lip of plate 216 and no further let-off will occur. Since the eyes of the thread guides are held at different elevations, the needles will pass the eyes successively. Consequently, as the eccentric mechanisms which operate the respective sliding carriages are substantially alike and as the threads must be let-off in different degrees to compensate for the difference in position of the thread guide eyes with respect to one another and to the needles, by adjusting the plates 216 the effective action of the two mechanisms may be properly timed.

50 A rod 221 is carried by the brackets 205 over which the thread T passes to keep it in contact with rod 211.

Secured to the arms 174 and 175 are curved springy plates 223 over which the threads pass 65 to clear the rods 171, 172.

Operation

By referring now particularly to Figs. 25 to 33 inclusive, the manner in which the needles, tongues, sinkers and thread-guide racking mechanisms are timed and operated to perform their knitting functions will be clear.

The solid line P indicates the path through which the upper end of the needle travels and, for convenience of illustration, a number of

points or positions have been marked on this path, as 1 to 9 inclusive. These positions correspond to Figs. 25 to 33 inclusive.

Starting with Fig. 25, it will be observed that at this time the needles will be at their lowest place, 1, in the path of travel P; loops L' will have been knocked-over and the threads T, T' will have been drawn through the loops L'; the needles, having reached their lowest point, are ready to rise. The sinkers will be moving forwardly in a straight line. It should here be stated that the double headed arrows on the sinkers and the arrows on the needles indicate movements of these parts in the directions of said arrows.

As the needles rise from the position 1 (Fig. 25) to position 2 (Fig. 26) they will rise through the second loops L² and the beard-hooks 164 will clear the second loops. Also the sinkers will continue their forward movement from the position of Fig. 25 to the position of Fig. 26. It will be seen that the direction of movement of the needles from point 1 to point 2 (Fig. 25 to Fig. 26) is in a straight or substantially straight line.

In passing from the position of Fig. 26 (point 2) to the position of Fig. 27 (point 3) the needles are not only moved longitudinally, but are bodily moved in an arc whose center is the axis of the rock-shaft 22. The sinkers are likewise rocked. As the thread-guides are stationary, the rocking downwardly of the sinkers as they are advanced from the position shown in Fig. 26 increases the distance between the sinker nibs 159, humps 161 and the thread-guides 178, 179, and thus prevents the threads when racked from lying across the sinkers at too sharp angles, which would tend to cause thread cutting or breaking, and at the same time permits the thread-guides to be located closer to the sinkers than has heretofore been possible in tricot knitting machines. This close location of the thread-guides to the sinkers also has the advantage that the up and down strokes of the needles may be proportionately shortened.

After the parts shall have reached the position shown in Fig. 27, the thread-guide racking mechanism operates to rack the guides. This racking can be set to occur at any time between the positions of Figs. 27 and 28.

In passing from the position of Fig. 26 to that of Fig. 28 the maximum per-cycle length of thread is drawn from the beams and the let-off mechanism carriages 214 will have been raised their maximum distance so that the threads will lie against the stop-lips 217.

In passing from the position of Fig. 27 to that of Fig. 28 (point 3 to point 4 on path P) the sinkers and needles will have completed their rocking movement in a clockwise direction in Figs. 27, 28 and the reverse rocking movement begins.

In passing from the position of Fig. 28 to the position of Fig. 29, the sliding carriages of the let-off mechanisms begin their thread take-up functions to take up excess thread which was let-off when the parts passed from the position of Fig. 26 to that of Fig. 28. Any slight difference between the amount of thread let-off and the amount to be taken up again is compensated for by the tension rods 211 and 213.

In passing from the position of Fig. 28 (point 4) via position of Fig. 29 (point 5) to the position of Fig. 30, the needles will hook the threads, continuing their combined downward and counter-clockwise rocking movement through position

Fig. 30 (point 6) to position of Fig. 31 (point 7) at which time the rocking motion ceases and the needles move down in a substantially straight line.

5 As soon as the needles and sinkers reach the position shown in Fig. 31, i. e., as soon as the point of the beard-hooks enters the sinkers, the hook-closer tongue 165 begins its lateral or hook-closing movement, completely closing the hooks 10 before position 32 is reached. The tongue is held in hook-closing position until the point of the hooks shall have passed through the loops L² (Fig. 32, point 8). At position Fig. 32 the sinkers are continuing their backward movement, the 15 limit of which is reached when the parts have come to the position of Fig. 33, point 9.

After the parts pass from the position of Fig. 33 and arrive at the position of Fig. 25, the thread-guides are again racked, thus completing one 20 cycle of operation.

From the foregoing it will be seen that with my improved sinker and sinker-and-needle rocking mechanism, the points of the hooks of the needles will enter the sinkers while the needle 25 ends will still be in the zone of the lower thread-guides.

The second embodiment of my invention

The second embodiment of my invention is best 30 disclosed in Figs. 40 to 46, by reference to which it will be seen that those parts which are substantially identical with parts of the first embodiment bear the same reference characters and need not here be further described.

35 In this embodiment shaft 14 is run at twice the speed of shaft 13, as in the preceding embodiment of my invention. The drive between shafts 13 and 14 may be of any suitable kind.

On the shaft 13 are fixed eccentrics 228 whose 40 eccentric straps 230 are pivoted to the cross-bar 232; the other end of this cross-bar is pivoted to the eccentric strap 231 for the eccentric 229. A slotted arm 233 is secured to the shaft 22. A link 234 is adjustably pivoted at 235 to the 45 cross-bar 232 and at 236 to the arm 233.

Fixed upright bearings 237 are provided, in which bearings tubular rods 238 work. Each rod 238 has a head 239 to which the cross-bar 232 is pivoted at 232a.

50 Eccentrics 240 (Fig. 46) are secured to shaft 13 and have straps 241 that are pivoted, at 242, to the needle-bar raising and lowering rods 71.

Bearings 243 are fixed to the rock shaft 22 (Fig. 43) at right angles to the bearings 10, 77 for the 55 guide rods 80. Secured to a second rock shaft 244 are bell-crank levers 245 having each a slotted arm 246 to which is pivotally adjustably connected, at 250, one end of an adjustable connecting rod 247. The other end of the rod 247 is

60 pivotally connected at 249 to the slide rod 248. Eccentrics 251 on shaft 13 and 252 on shaft 14 have their respective straps 257 and 258 pivoted to the ends of cross-bars 253.

Each cross-bar 253 is pivoted, at 253a, to the 65 head 261 on a tubular shank or rod 260 that works in a fixed bearing 259.

A link 254 is pivoted at 256 to the bell-crank lever 245 and adjustably pivoted at 255 to the cross-bar 253.

70 The shaft 13 is further provided with eccentrics 262 whose straps 263 are pivoted to one end of bell-crank levers 265 that are mounted on a third rock-shaft 264. The other end of each lever 265 is slotted as at 266 and to this end is adjustably pivoted, at 272, an adjustable connecting rod 270

that is also pivoted to a rod 269, as at 271. The rod 269 slides in a bearing 268 on a bracket 257 that is secured on rock-shaft 22. The rod 269 is connected with the sinker bar 101, as is the rod 102 in the first embodiment of the invention.

The thread let-off and take-up mechanism is substantially the same as that of the first form of the invention, differing only in this, that the cross-bar 273 of the lower mechanism is slotted as at 274 and is pivoted at 273^a to the head 44 and, further, the link 275 is adjustably pivoted to the cross-bar as at 276.

Similarly, the cross-bar 277 of the upper mechanism is slotted as at 278, and is pivoted at 277^a to the head 59. The cross-bar 277 has pivotally connected to it, at 280, a link 279, which link is in turn adjustably pivoted to the arm 63.

In the second embodiment of my invention the fabric guide roll 283 is carried on levers 282 which are mounted on a rock-shaft 281 and are connected with slotted arms, 284, secured to rock-shaft 22, by means of links 295. The links are pivoted at 286 to the levers 282 and are adjustably pivoted at 287 to the arms 284.

The cloth from the sinkers 158 passes over rod 283 to the usual take-up roll 289 on shaft 288. Means for operating the cloth take-up roll 289 is well known and is not a part of the present invention.

From the foregoing it will be seen that as shaft 22 rocks to tilt the bearings 70, 71, 243, 268, it will impart a swinging motion to rod 283 sufficient (with proper adjustment of pivot 287) to keep the cloth 290 taut.

By providing the adjustable pivotal connections 235, 236, 255, 272, 276, 280, as well as those between elements 275, 48 and 279, 63, it is possible to obtain a very accurate adjustment of the movements required to effect the knitting operations rapidly.

In Figs. 47 to 55 inclusive I have diagrammatically illustrated one cycle of operation of the machine of the second embodiment of my invention.

Starting with the needles 165 at their lowest position (Fig. 47) the sinkers 158 will be moving forward. The needles will have knocked over and pulled a new loop through the loop L' that was previously knocked over.

On passing from the position of Fig. 47 to that of Fig. 48, the needles rise in a straight, or approximately straight, line, while the sinkers continue to advance in a straight, or approximately straight line. The loops L' and L² are held down by the sinker nibs as the needles rise through the second loop L².

Passing from the position of Fig. 48, the needles rise to the position of Fig. 49, and the sinkers continue their forward movement. As the sinkers and needles pass from the position of Fig. 48 the rock-shaft 22 begins to rock clockwise in Fig. 40, causing the sinkers to swing downwardly away from the thread guides 178, 179, and causing the needles to tilt so that their free ends will follow the upward (lower part) curved part of path P.

The thread guides having been racked at the position of Fig. 47, as the parts pass from the position of Fig. 49 to the position of Fig. 50, the needle shanks back of the hooks will draw the threads T, T'.

By the time position Fig. 50 shall have been reached, the sinkers will have reached the limit of the forward strokes and on passing from the position of Fig. 50 to the position of Fig. 51 the sinkers will be moving backwards, the needles will have reached the upper limits of their strokes;

the rocking of shaft 22 will now be rocked counter-clockwise so that by the time the parts reach the position of Fig. 53 the reverse rocking of shaft 22 will cease.

Passing from the position of Fig. 51 to the position of Fig. 52, the needles will hook the threads and the tongues 165 will be starting on their hook-closing movement. By the time the parts reach the position of Fig. 53 the hooks will have been closed by the tongues and will remain in the hook-closed position until the parts pass the position of Fig. 54 and the hooks shall have entered the loops L².

Passing from the position of Fig. 53 via position of Fig. 54 to the position of Fig. 55, the sinkers will move back to their zero position, Fig. 55.

The needles will be moving down at position Fig. 55, and just about to cast off the loop L². Moving from the position Fig. 55 to position Fig. 47 completes a cycle of operation.

The movements of the needles, sinkers and tongues illustrated in Figs. 47 to 55 inclusive are not absolute, but may be varied somewhat without rendering the machine inoperative for its intended purposes.

It should be understood that the eccentric means for rocking the shaft 22, operating the needle and tongue bar, etc., etc., are duplicated at each end of the machine. Also the proportions or dimensions and relative positions of the eccentrics, indicated in the drawings, are approximate only and may be varied somewhat to attain the most effective results desired.

By the term "stationary thread guides" I mean guides which do not move in a front-to-back direction to place thread around the needles, but rack only across the needles.

It may, under some conditions, be found desirable to impart only a rectilinear movement to the sinkers, instead of a combined rectilinear and rocking movement. In that event the bracket 267' is fitted loosely on the shaft 22 and is adjustably held at any desired angle to the vertical radius of shaft 22 by means of an adjustable rod 291 which is pivoted at 292 to the bracket 267' and at 293 to a fixed bar 294 of the machine. By lengthening or shortening the rod 291 through a turnbuckle joint 295 the bracket 267' may be set to work the sinker at more or less of an inclination to the horizontal as may be desired.

From the foregoing description taken in connection with the accompanying drawings it is thought the construction, operation and advantages of my invention will be clear to those skilled in the art.

What I claim is:

1. In a knitting machine employing thread guides and means for racking the same: a rock shaft; a needle-bar carried by said rock shaft; a tongue bar carried by said rock shaft; a sinker bar carried by said rock shaft; hook needles on said needle bar; hook-closing tongues operatively connected to said tongue bar; sinkers on said sinker bar; means for imparting movements to said needle bar to effect reciprocation of said needles in their lengthwise direction; means for imparting movements to said sinker bar to move the sinkers forwardly and backwardly; means for actuating said tongue bar to cause the tongues to close and open the needle hooks; means for rocking said rock shaft to impart an arcuate movement to said needles, tongues and sinkers; the aforesaid movement-imparting means being cooperatively connected together to cause said

needles, said tongues, and said sinkers to perform, with said thread guides, knitting operations.

2. In a knitting machine employing thread guides and means for racking the same: a rock shaft; a needle bar carried by said rock shaft; a tongue bar carried by said rock shaft; a sinker bar carried by said rock shaft; hook needles on said needle bar; hook-closing tongues operatively connected to said tongue bar; sinkers on said sinker bar; means for imparting movements to said needle bar to effect reciprocation of said needles in their lengthwise direction; means for imparting movements to said sinker bar to move the sinkers forwardly and backwardly; means for actuating said tongue bar to cause the tongues to close and open the needle hooks; means for rocking said rock shaft to impart an arcuate movement to said needles, tongues and sinkers; said means for rocking said rock shaft including an arm on said rock shaft, two eccentric shafts, an eccentric on each eccentric shaft, eccentric straps for said eccentrics, a cross bar pivotally connected to said eccentric straps, and a link between said cross bar and said arm; the aforesaid movement-imparting means being cooperatively connected together to cause said needles, said tongues, and said sinkers to perform, with said thread guides, knitting operations.

3. In a knitting machine employing thread guides and means for racking the same: a rock shaft; a needle bar carried by said rock shaft; a tongue bar carried by said rock shaft; a sinker bar carried by said rock shaft; hook needles on said needle bar; hook-closing tongues operatively connected to said tongue bar; sinkers on said sinker bar; means for imparting movements to said needle bar to effect reciprocation of said needles in their lengthwise direction; means for imparting movements to said sinker bar to move the sinkers forwardly and backwardly; means for actuating said tongue bar to cause the tongues to close and open the needle hooks; means for rocking said rock shaft to impart an arcuate movement to said needles, tongues and sinkers; said means for rocking said rock shaft including an arm on said rock shaft, two eccentric shafts, an eccentric on each eccentric shaft, eccentric straps for said eccentrics; a cross bar pivotally connected to said eccentric straps, and a link between said cross bar and said arm; the aforesaid movement-imparting means being cooperatively connected together to cause said needles, said tongues, and said sinkers to perform, with said thread guides, knitting operations; and means for adjustably pivoting said link to said arm.

4. In a knitting machine employing thread guides and means for racking the same: a rock shaft; a needle bar carried by said rock shaft; a tongue bar carried by said rock shaft; a sinker bar carried by said rock shaft; hook needles on said needle bar; hook-closing tongues operatively connected to said tongue bar; sinkers on said sinker bar; means for imparting movements to said needle bar to effect reciprocation of said needles in their lengthwise direction; means for imparting movements to said sinker bar to move the sinkers forwardly and backwardly; means for actuating said tongue bar to cause the tongues to close and open the needle hooks; means for rocking said rock shaft to impart an arcuate movement to said needles, tongues and sinkers; said means for rocking said rock shaft including an arm on said rock shaft, two eccentric shafts, an eccentric on each eccentric shaft, eccentric

straps for said eccentrics; a cross bar pivotally connected to said eccentric straps, and a link between said cross bar and said arm; the aforesaid movement-imparting means being cooperatively connected together to cause said needles, said tongues, and said sinkers to perform, with said thread guides, knitting operations; and means for adjustably pivoting said link to said arm and to said cross bar.

5. In a knitting machine employing thread guides and means for racking the same: a rock shaft; a needle bar carried by said rock shaft; a tongue bar carried by said rock shaft; a sinker bar carried by said rock shaft; hook needles on said needle bar; hook-closing tongues operatively connected to said tongue bar; sinkers on said sinker bar; means for imparting movements to said needle bar to effect reciprocation of said needles in their lengthwise direction, said means for imparting movements to said needle bar including an eccentric shaft, an eccentric on said shaft, needle-bar-carrying rods, and an eccentric strap connecting said eccentric to said needle-bar-carrying rods; means for imparting movements to said sinker bar to move the sinkers forwardly and backwardly; means for actuating said tongue bar to cause the tongues to close and open the needle hooks; means for rocking said rock shaft to impart an arcuate movement to said needles, tongues and sinkers; the aforesaid movement-imparting means being cooperatively connected together to cause said needles, said tongues, and said sinkers to perform, with said thread guides, knitting operations.
6. In a knitting machine employing thread guides and means for racking the same: a rock shaft; a needle bar carried by said rock shaft; a tongue bar carried by said rock shaft; a sinker bar carried by said rock shaft; hook needles on said needle bar; hook-closing tongues operatively connected to said tongue bar; sinkers on said sinker bar; means for imparting movements to said needle bar to effect reciprocation of said needles in their lengthwise direction; means for imparting movements to said sinker bar to move the sinkers forwardly and backwardly, said means for imparting movements to said sinker bar including a cam shaft, a cam on said cam shaft, and operative connections between said cam and said sinker bar; means for actuating said tongue bar to cause the tongues to close and open the needle hooks; means for rocking said rock shaft to impart an arcuate movement to said needles, tongues and sinkers; the aforesaid movement-imparting means being cooperatively connected together to cause said needles, said tongues, and said sinkers to perform, with said thread guides, knitting operations.

7. In a knitting machine employing thread guides and means for racking the same: a rock shaft; a needle bar carried by said rock shaft; a tongue bar carried by said rock shaft; a sinker bar carried by said rock shaft; hook needles on said needle bar; hook-closing tongues operatively connected to said tongue bar; sinkers on said sinker bar; means for imparting movements to said needle bar to effect reciprocation of said needles in their lengthwise direction; means for imparting movements to said sinker bar to move the sinkers forwardly and backwardly; means for actuating said tongue bar to cause the tongues to close and open the needle hooks, said tongue-bar-actuating means including a cam shaft, a cam on said cam shaft, and operative connections between said cam and said tongue bar; means

15

for rocking said rock shaft to impart an arcuate movement to said needles, tongues and sinkers; the aforesaid movement-imparting means being cooperatively connected together to cause said needles, said tongues, and said sinkers to perform, with said thread guides, knitting operations.

8. In a knitting machine employing thread guides and means for racking the same: a rock shaft; a needle bar; a tongue bar; a sinker bar; means for mounting said tongue bar and said sinker bar on said rock shaft, said mounting means including a bearing unit mounted on said rock shaft on which unit said sinker bar is carried and by which said tongue actuating means is in part carried; hook needles on said needle bar; hook-closing tongues operatively connected to said tongue bar; sinkers on said sinker bar; means for imparting movements to said needle bar to effect reciprocation of said needles in their lengthwise direction; means for imparting movements to said sinker bar to move the sinkers forwardly and backwardly; means for actuating said tongue bar to cause the tongues to close and open the needle hooks; means for rocking said rock shaft to impart an arcuate movement to said needles, tongues and sinkers, the aforesaid movement-imparting means being cooperatively connected together to cause said needles, said tongues, and said sinkers to perform, with said thread guides, knitting operations.

9. In a knitting machine employing thread guides; a shaft; a needle bar carried by said shaft; hook needles mounted on said needle bar; a tongue bar carried by said shaft; tongues carried by said needles and operatively engaging said tongue bar; a sinker bar carried by said shaft; sinkers mounted on said sinker bar; means for moving said needle bar, said sinker bar and said tongue bar to impart reciprocative movements to said sinkers, needles and tongues in a direction substantially tangent to said rock shaft; and means for imparting to said tongue bar hook-closing and opening movements in timed relation to the reciprocations of said needles and tongues to effect knitting functions.

10. In a knitting machine employing thread guides; a shaft; a needle bar carried by said shaft; hook needles mounted on said needle bar; a tongue bar carried by said shaft; tongues carried by said needles and operatively engaging said tongue bar; a sinker bar carried by said shaft; sinkers mounted on said sinker bar; means for moving said needle bar, said sinker bar and said tongue bar to impart reciprocative movements to said sinkers, needles and tongues in a direction substantially tangent to said shaft; and means to rock said shaft about its axis thereby to rock said needle bar and said tongue bar; and means for imparting to said tongue bar hook-closing and opening movements in timed relation to the reciprocations of said needles and tongues to effect knitting functions.

11. In a knitting machine which employs a supporting frame, sinkers, thread guides, hook needles and needle-hook closers, the improvement which includes: a suitably supported rock-shaft itself having bearings; means for rocking said rock-shaft; needle-bar-carrying shafts reciprocatingly mounted in said rock-shaft bearings; a needle bar secured to said needle-bar-carrying shafts; hook needles mounted on said needle-bar; means operable in harmony with the rocking of said rock-shaft and the reciprocations of said needle-bar-carrying shafts for

75

16

operating said needle-hook-closures to close and open the hooks of said needles to effect knitting operations.

12. The machine of claim 11 wherein the needle-bar-carrying shaft-bearings are offset with respect to the axis of said rock-shaft.

13. The machine of claim 11 wherein brackets are secured on said rock-shaft and a hook-closer bar is carried by said brackets to which bar hook-closers are operatively connected.

14. The machine of claim 11 wherein the needle-bar-carrying shaft-bearings are offset with respect to the axis of said rock-shaft and wherein brackets are secured on said rock-shaft and a hook-closer-carrying bar is carried by said brackets on which bar the hook-closers are movably mounted.

15. The machine of claim 11 wherein said means for reciprocating said needle-bar-carrying shafts includes an eccentric drive and said rock-shaft-rocking means includes a double eccentric drive, said drives being constructed to impart one complete oscillation to the rock-shaft to one complete reciprocation of the needle-bar-carrying shafts.

16. The machine of claim 11 wherein the needle-bar-carrying shaft-bearings are offset with respect to the axis of the rock-shaft and wherein said means for reciprocating said needle-bar-carrying shafts includes an eccentric drive and said rock-shaft-rocking means includes a double eccentric drive.

17. The machine of claim 11 wherein brackets are secured on said rock-shaft and a hook-closer-carrying bar is carried by said brackets on which bar hook-closers are movably mounted.

18. The machine of claim 11 wherein the needle-bar-carrying shaft-bearings are offset with respect to the axis of said rock-shaft and wherein brackets are secured on said rock-shaft and a hook-closer-carrying bar is carried by said brackets on which bar the hook-closers are movably mounted.

19. In a knitting machine: a rock shaft, a needle bar carried by said rock shaft; needles carried by said needle bar; a tongue bar and tongues carried by said rock shaft; means for simultaneously imparting to said needle bar and to said tongue bar reciprocating movements in a direction substantially tangential to said shaft; and means for imparting to said tongue bar hook-closing and opening movements in a direction transverse to said first mentioned direction.

20. In a knitting machine: a rock shaft; a needle bar carried by said rock shaft; needles carried by said needle bar; a tongue bar and tongues carried by said rock shaft; means for simultaneously imparting to said needle bar and to said tongue bar reciprocating movements in a direction substantially tangential to said shaft and in an arc concentric with said shaft; and means for imparting to said tongue bar hook-closing and opening movements in a direction transverse to said first mentioned direction.

21. In a knitting machine: a rock shaft; a needle bar carrying hook knitting needles; a tongue bar and tongues for said needles; bearings on said shaft disposed tangentially of the rock shaft; needle-bar and tongue-bar supports mounted in said bearings; means for imparting to said needles and to said tongues reciprocating movements, in the direction of their lengths, tangentially to said rock shaft; means for imparting to said needles and to said tongues a rocking motion about the axis of said rock shaft; and

means for imparting transverse movements to said tongues to close and open the needle hooks; and means coordinating the aforesaid movements to effect knitting operations.

22. In a knitting machine wherein hook needles, thread guides and sinkers are employed: the improvement which includes means to cause the needles to pass up through the sinkers, then through the thread guides to the front of the same without hooking the thread, then again through the thread guides to the back of the same and downwardly to hook the threads and carry the threads into the sinkers and through previously formed loops on the needles; and means secured to the needles for closing the hooks when drawing the thread through the loops.

23. In a knitting machine having thread guides, sinkers, and sinker-nibs: two eccentric shafts each having eccentrics and traveling at different speeds; eccentric-straps for said eccentrics; a cross bar connecting said eccentric-straps; an oscillatable shaft having bearings; a set of needle - bar - carrying shafts reciprocatingly mounted in said bearings; operative connection between said oscillatable shaft and said cross bar; a needle bar carried by said set of needle-bar-carrying shafts; hook needles on said needle bar; means for reciprocating said needle-bar-carrying shafts; and means for closing the hooks of said needles while the hooks are in the sinkers and nibs.

24. In a knitting machine wherein hook needles, hook-closing tongues, sinkers, sinker nibs and thread guides are employed, the improvement which includes: a needle bar carrying the needles; eccentric-operated reciprocating shafts carrying said needle bar; oscillatable bearings for said shafts; means to oscillate said bearings as said shafts are reciprocated and in timed relation to the same to cause said needles to pass through between the thread guides on the up strokes of the needles and to hook the threads on the down strokes of the needles; and means to operate the tongues to close the hooks of the needles as they approach the sinkers on the down strokes and while drawing the threads through a previously formed loop about the needles and knocking over.

25. In a knitting machine employing movable sinkers having nibs and knock-over portions, hook knitting needles, hook closers, and thread guides: means for imparting a longitudinal and a combined longitudinal and transverse movement to the needle hooks; means for imparting a longitudinal movement and a combined longitudinal and transverse movement to the sinkers, the sinker movements being generally in a horizontal direction; and means for coordinating and combining the aforesaid sinker and needle movements so that as the needles move upwardly the sinkers will move forwardly toward the thread guides and as they approach the thread guides the sinkers will dip below the thread guides while the hook ends of the needles will pass forwardly-upwardly between the guides and then the sinkers will be returned to their initial position as the needles move their hook ends downwardly-rearwardly between the thread guides to hook the thread and carry it to the sinkers and through loops to be knocked over; and means for operating the hook closers to close the hooks while the hooks are passing down between the sinkers and into said loops.

26. In a knitting machine employing movable sinkers having nibs and knock-over portions, hook

knitting needles, hook closers, and thread guides: means for imparting a longitudinal and a combined longitudinal and transverse movement to the needle hooks; means for imparting a longitudinal movement and a combined longitudinal and transverse movement to the sinkers, the sinker movements being generally in a horizontal direction; and means for coordinating and combining the aforesaid sinker and needle movements so that as the needles move upwardly the sinkers will move forwardly toward the thread guides and as they approach the thread guides the sinkers will dip below the thread guides while the hook ends of the needles will pass forwardly-upwardly between the guides and then the sinkers will be returned to their initial position as the needles move their hook ends downwardly-rearwardly between the thread guides to hook the thread and carry it to the sinkers and through loops to be knocked over; and means for operating the hook closers to close the hooks while the hooks are passing down between the sinkers and into said loops; and means for racking the thread guides at proper times to effect knitting operations.

27. The method of operating a knitting machine having hook needles, tongues carried by the needles, sinkers, and thread guides, said method including: operating the needles with their tongues so as to pass the hooks and tongues up through the sinkers in a substantially straight line; then forwardly between the thread guides, without hooking the thread, to clear the thread guides; racking the thread guides; then passing the needles back again between the thread guides and downwardly to hook the threads; continuing the downward movement of the needles and tongues and as the needle hooks enter the sinkers moving the tongues to close the hooks and holding the hooks closed until the hooks have passed into a previously formed loop on the needles; again racking the thread guides and knocking over.

28. The method of knitting on a knitting machine which employs hook needles, thread guides, sinkers, and hook-closing tongues: said method including moving the needles together with the tongues upwardly through the sinkers and forwardly between the thread guides to engage the threads with the shanks of the needles on the side of the needles opposite the hooks; then, after the needles have passed the thread guides, racking the thread guides; then passing the needles and tongues back between the thread guides and downwardly to hook the threads and carry them into the sinkers; moving the tongues to close the hooks as the hooks enter the sinkers and holding the hooks closed until the threads have been drawn through the previously formed loops on the needles and said loops have been knocked over, again racking the thread guides; thus completing a cycle of operation.

29. The method of knitting with a knitting machine that employs hook needles, hook-closing tongues, sinkers, and thread guides: said method including operating the machine to cause the needles to rise through the sinkers and move their hooks through a loop-path forwardly between the thread guides to engage the threads with the front of the needle shanks; then, when the needles have passed the thread guides along the lower part of the loop-path, racking the thread guides; completing the movement of the needle hooks over the upper part of the loop-path and moving the needles backwardly between

19

the thread guides and downwardly to hook the threads and carry them into the sinkers; racking the thread guides when the needles are again clear of the same; moving the tongues to close the hooks as the hooks enter the sinkers and keeping the hooks closed until the hooks have passed into the previously formed loops about the needles; and knocking over, thus completing a cycle of operation of the machine.

30. In a knitting machine wherein thread guides, longitudinally movable sinkers, hook knitting needles, and hook closers are employed, the improvement which includes: the method of operating the sinkers which comprises imparting to the sinkers a forward longitudinal and a curvilinear movement by virtue of which the sinkers are moved forwardly toward the guides and then as they approach the guides the sinkers will be lowered beneath the guides while continuing their forward movement and then returning the sinkers to their retracted position along the same path over which the sinkers travelled in moving forward.

31. In a knitting machine employing movable sinkers having ribs, hook knitting needles, hook closers and thread guides, the method of operating the aforesaid sinkers, needles and hook closers which includes: moving the needles up between the sinkers while simultaneously moving the sinkers forwardly until the hook ends of the needles begin to project above the sinker ribs and approach the thread guides; then while continuing the forward movement of the sinkers causing the sinkers to dip downwardly as the sinker ribs pass below the thread guides until the needles shall have reached approximately their upward limit of movement; and then returning the sinkers to their initial position while moving the needles on their return strokes.

32. In a knitting machine employing movable sinkers having ribs, hook knitting needles, hook closers and thread guides, the method of operating the aforesaid sinkers, needles and hook closers which includes: moving the needles up between the sinkers while simultaneously moving the sinkers forwardly until the hook ends of the needles begin to project above the sinker ribs and approach the thread guides; then while continuing the forward movement of the sinkers causing the sinkers to dip downwardly as the sinker ribs pass below the thread guides until the needles shall have reached approximately their upward limit of movement; and then returning the sinkers to their initial position while moving the needles on their return strokes; and, while the sinkers are moving forwardly-downwardly, imparting to the needles a lateral-forward movement to pass forwardly between the thread guides, and, while the sinkers are returning, imparting a lateral-backward movement to the needles between the thread guides to hook the thread; and operating the hook closers to close the needle hooks while the points of the hooks are between the sinkers and before the points enter the loop that is to be knocked over on the down stroke of the needles.

33. In a knitting machine wherein is provided hook knitting needles, hook-closing tongues, sinkers, and thread guides: a shaft; at least two bearing units spaced apart, each of said units including a sleeve secured to said shaft, a rearwardly projecting bracket, an upper socket and a lower socket carried by said rearwardly projecting bracket, an upwardly projecting bracket, two parallel slide-rod bearings carried by said

20

upwardly projecting bracket, the axes of which slide-rod bearings lie parallel to the axis of said sleeve, a transverse bearing carried by said upwardly projecting bracket; sinker-bar-supporting rods slidable in said transverse bearings; a sinker bar carried by said sinker-bar-supporting rods; slide rods mounted in said slide-rod bearings; pivot spindles mounted, one in each said upper and lower sockets; a bell crank lever mounted on each pivot spindle; means operatively connecting one arm of each upper bell crank lever to one of said slide rods; means operatively connecting one arm of each lower bell crank lever to the other of said slide rods; a connecting rod between the other arm of each upper bell crank lever and said sinker bar; slide arms connected at one of their ends to other arms of the respective lower bell crank levers and carrying vertical bearings at their free ends, said units including slide-ways for said slide arms; a tongue bar having guide rods slidably mounted in said vertical bearings; a needle bar; means on said shaft for supporting said needle bar for back and forth and up and down movement; means for raising and lowering said needle bar; and means to operate said slide rods to move said sinker bar and said tongue bar back and forth in timed relation to each other and to the up and down movements of the needle to effect knitting operations.

34. A knitting machine according to claim 33 wherein the slide rod operating means includes cam-actuated levers operatively connected to said slide rods.

35. A knitting machine according to claim 33 wherein said needle bar supporting and raising and lowering means includes bearings on said shaft, raising and lowering rods in said last named bearings, an eccentric shaft, eccentrics on said eccentric shaft, and connections between said eccentrics and said raising and lowering rods.

36. A knitting machine according to claim 33 wherein the thread guides are movable back and forth only in a direction to lay the thread across the needles; and means are provided for rocking the first mentioned shaft in timed relation to said needle-bar-raising means and said slide-rod-operating means to effect knitting operations.

37. A knitting machine according to claim 33 wherein said slide rod operating means includes cam-actuated levers operatively connected to said slide rods; and means for rocking the first mentioned shaft in timed relation to said needle-bar-raising means and said slide-rod operating means to effect knitting operations.

38. A knitting machine according to claim 33 wherein said needle bar supporting and raising and lowering means includes bearings on said shaft, raising and lowering rods in said last named bearings, an eccentric shaft, eccentrics on said eccentric shaft, and connections between said eccentrics and said raising and lowering rods, and means for rocking the first mentioned shaft in time relation to said needle-bar-raising means and said slide-rod operating means to effect knitting operations.

39. In a knitting machine: a rock shaft; means to rock said shaft; bearing units secured to said rock shaft and each having bearings offset from the axis of said rock shaft; a needle bar; needle-bar-carrying rods reciprocably mounted in said bearings; means to reciprocate said rods; hook needles on said needle bar; said bearing units each also including a second set of bearings offset from the axis of said rock shaft; tongue-

bar-carrying rods mounted in said second set of bearings; a tongue bar carried by said tongue-bar-carrying rods; hook-closing tongues anchored in said needles and operatively connected to said tongue bar; and means for moving said second set of bearings to cause said tongues to close and open the hooks at proper times to effect knitting operations.

40. In a knitting machine: a rock shaft; means to operate said rock shaft; a first set of bearings secured to said rock shaft; a second set of bearings secured to said rock shaft; a needle bar; a tongue bar; sinkers; needles on said needle bar and having hooks; tongues anchored in said hooks and operatively connected with said tongue bar; needle-bar-carrying rods mounted in said first set of bearings; tongue-bar-carrying rods mounted in said second set of bearings; means to effect movements of said needle bars and said tongue bar and said sinkers to cause said needles and said tongues to pass through a knitting cycle of movement.

41. In a knitting machine: a rock shaft; means to operate said rock shaft; a first set of bearings secured to said rock shaft; a second set of bearings secured to said rock shaft; a needle bar; a tongue bar; sinkers; needles on said needle bar and having hooks; tongues anchored in said hooks and operatively connected with said tongue bar; needle-bar-carrying rods mounted in said first set of bearings; tongue-bar-carrying rods mounted in said second set of bearings; at least one beam; thread guides; thread guide racking mechanism; a thread let-off and take-up mechanism located between the beam and the thread guides; a cloth take-up mechanism; and means to effect movements of said needle bars, said tongue bar, said thread racking mechanism, said sinkers, said thread let-off and take-up mechanism and said cloth take-up mechanism to effect knitting operations and maintain the thread and cloth taut.

42. In a knitting machine wherein are provided at least one beam, hook needles, hook-closing tongues, thread guides, sinkers, thread let-off and cloth take-up mechanisms, the improvement which includes: a rock shaft; a first set of bearings carried by said rock shaft; a second set of bearings carried by said rock shaft; a needle bar having rods mounted in said first set of bearings on which bar said needles are mounted; a tongue bar having rods mounted in said second set of bearings to which bar said tongues are operatively connected; eccentric operated means for effecting operation of said needle bar; means for effecting operation of said tongue bar; means for operating said sinker; means for racking said thread guides; and means for coordinating the operations of all said means for effecting knitting operations.

43. In a knitting machine wherein thread guides, hook needles, sinkers and hook-closing tongues are employed, the improvement which includes: a rock shaft; means supporting said needles, said sinkers and said tongues on said as the other; eccentrics on said eccentric shafts; two eccentric shafts, one turning twice as fast as the other; eccentrics on said eccentric shafts, straps for said eccentrics; a cross-bar pivoted at its ends to the respective straps; a stationary bearing; a rod operating in said stationary bearing and having a head to which said cross-bar is pivoted; and a link between said arm and said cross-bar.

44. In a knitting machine wherein thread

guides, hook needles, sinkers and hook-closing tongues are employed, the improvement which includes: a rock shaft; means supporting said needles, said sinkers and said tongues on said rock shaft; an arm secured to said rock shaft; two eccentric shafts, one turning twice as fast as the other; eccentrics on said shaft; straps for said eccentrics; a cross-bar pivoted at its ends to the respective straps; a stationary bearing; a rod operating in said stationary bearing and having a head to which said cross-bar is pivoted; and a link pivotally and adjustably connected to said arm and to said cross-bar.

45. In a knitting machine wherein thread guides, hook needles, sinkers and hook-closing tongues are employed, the improvement which includes: a rock shaft; a bearing carried by said rock shaft; a rod reciprocative in said bearing; a bearing carried by said rod; a guide rod reciprocal in said rod-carried bearing; a tongue bar to which said rod is secured; two eccentric shafts, one of which turns at twice the speed of the other; an eccentric on each eccentric shaft; straps for said eccentrics; a cross-bar pivoted to the straps of a pair of said eccentrics; a stationary bearing; a rod operating in said stationary bearing and having a head to which said cross-bar is pivoted; and an operative connection between said cross-bar and said reciprocative rod.

46. In a knitting machine wherein thread guides, hook needles, sinkers and hook-closing tongues are employed, the improvement which includes: a rock shaft; a bearing mounted on said rock shaft; a rod reciprocative in said bearing; a sinker bar carried by said rod; a pivoted lever; a connecting rod between said rod and one arm of said lever; an eccentric shaft; an eccentric on said eccentric shaft; and an eccentric strap connecting said eccentric with the other arm of said lever.

47. In a knitting machine wherein is provided knitting needles and tongues, thread guides, sinkers, a beam, and means for operating the same to effect knitting operations, the improvement which comprises a thread let-off mechanism that includes: stationary supports; a spring-cushioned bar carried by said supports and over which thread from the beam passes; another spring-cushioned bar carried by said supports and under which said thread passes; sliding carriages mounted on said supports; a bar carried by said sliding carriages to engage the thread at a place between said spring cushioned bars; and means to actuate said carriages to cause the bar carried thereby to let-off and take-up thread accordingly as the carriages are moved in one direction or the reverse.

48. In a knitting machine wherein is provided knitting needles and tongues, thread guides, sinkers, a beam, and means for operating the same to effect knitting operations, the improvement which comprises a thread let-off mechanism that includes: stationary supports; a spring-cushioned bar carried by said supports and over which thread from the beam passes; another spring-cushioned bar carried by said supports and under which said thread passes; sliding carriages mounted on said supports; a bar carried by said sliding carriages to engage the thread at a place between said spring cushioned bars; means to impart reciprocations of constant magnitude to said carriages; and means to regulate the effective actions of said carriage-carried bar on the thread.

23

49. In a knitting machine wherein is provided knitting needles and tongues, thread guides, sinkers, a beam, and means for operating the same to effect knitting operations, the improvement which comprises a thread let-off mechanism that includes: stationary supports; a spring-cushioned bar carried by said supports and over which thread from the beam passes; another spring-cushioned bar carried by said supports and under which said thread passes; sliding carriages mounted on said supports; a bar carried by said sliding carriages to engage the thread at a place between said spring cushioned bars; means to impart reciprocations of constant magnitude to said carriages; and means to regulate the effective actions of said carriage-carried bar on the thread, the last named means comprising a straight edge on said carriage-carried bar and an adjustable fixedly-located straight edge cooperating with the straight edge on said carriage-carried bar to stop the let-off of the thread before the carriages complete their thread let-off strokes.

50. In a knitting machine wherein is provided knitting needles and tongues, thread guides, sinkers, a beam, and means for operating the same to effect knitting operations, the improvement which comprises a thread let-off mechanism that includes: stationary supports; a spring-cushioned bar carried by said supports and over which thread from the beam passes; another spring-cushioned bar carried by said supports and under which said thread passes; sliding carriages mounted on said supports; a bar carried by said sliding carriages to engage the thread at a place between said spring-cushioned bars; and means to actuate said carriages to cause the bar carried thereby to let-off and take-up thread accordingly as the carriages are moved in one direction or the reverse; said carriage-actuating means including eccentric-drive mechanism.

51. In a knitting machine wherein is provided knitting needles and tongues, thread guides, sinkers, a beam, and means for operating the same to effect knitting operations, the improvement which comprises a thread let-off mechanism that includes: stationary supports; a spring-cushioned bar carried by said supports and over which thread from the beam passes; another spring-cushioned bar carried by said supports and under which said thread passes; sliding carriages mounted on said supports; a bar carried by said sliding carriages to engage the thread at a place between said spring-cushioned bars; and means to actuate said carriages to cause the bar carried thereby to let-off and take-up thread accordingly as the carriages are moved in one direction or the reverse; said carriage-actuating means including eccentric-drive mechanism, said eccentric-drive mechanism comprising two eccentric shafts, one turning twice as fast as the other; eccentrics on said shafts, eccentric straps for said eccentrics, a cross-bar connecting said straps, rocking levers, links adjustably connected to said cross-bars and to said rocking levers, and connecting rods connecting said rocking levers to said carriages.

52. In a knitting machine wherein is provided knitting needles and tongues, thread guides, sinkers, a beam, and means for operating the same to effect knitting operations, the improvement which comprises a thread let-off mechanism that includes: stationary supports; a spring-cushioned bar carried by said supports and over which thread from the beam passes; another spring-

24

cushioned bar carried by said supports and under which said thread passes; sliding carriages mounted on said supports; a bar carried by said sliding carriages to engage the thread at a place between said spring-cushioned bars; and means to actuate said carriages to cause the bar carried thereby to let-off and take-up thread accordingly as the carriages are moved in one direction or the reverse; said carriage-actuating means including eccentric-drive mechanism, said eccentric-drive mechanism comprising two eccentric shafts, one turning twice as fast as the other; eccentrics on said shafts, eccentric straps for said eccentrics, a cross-bar connecting said straps, rocking levers, links adjustably connected to said cross-bars and to said rocking levers, and connecting rods connecting said rocking levers to said carriages; fixed bearings, rods slidably in said fixed bearings and having heads to which said cross-bars are pivoted.

53. In a knitting machine wherein is employed two beams, sinkers having nibs, means for moving the sinkers forwardly and backwardly, hook knitting needles, two sets of thread guides, one set being located in advance of the other and means to move the thread guides to rack the threads, the improvement which includes: a thread let-off, take-up and tension mechanism for each set of guides; means for moving said needles up and down between adjacent sinkers to cause the needle hooks to pass up above the sinkers and forwardly between the thread guide ends in succession to draw thread with the shanks of the needles and then move backwardly-downwardly to hook racked threads; and means to operate said thread let-off, take-up and tension mechanisms successively to cooperate with the needles and maintain the threads taut:

54. In a knitting machine wherein is employed two beams, sinkers having nibs, means for moving the sinkers forwardly and backwardly, hook knitting needles, two sets of thread guides, one set being located in advance of the other and means to move the thread guides to rack the threads, the improvement which includes: a thread let-off, take-up and tension mechanism for each set of guides; means for moving said needles up and down between adjacent sinkers to cause the needle hooks to pass up above the sinkers and forwardly between the thread guide ends in succession to draw thread with the shanks of the needles and then move backwardly-downwardly to hook racked threads; and means to operate said thread let-off, take-up and tension mechanisms successively to cooperate with the needles and maintain the threads taut, said thread let-off, take-up and tension mechanisms each including a separate means to adjust their respective actions to compensate for the different positions of the thread guides and the times the threads therefrom are engaged by the needles in their thread-drawing and thread-hooking movements.

55. In a knitting machine wherein is employed, beams, sinkers, means for moving the sinkers back and forth, thread guides, and knitting needles, the improvement which includes: a cloth take-up roll; a rock shaft on which said sinkers and needles are carried; means to rock said shaft to tilt the needles and sinkers; a cloth tension comprising a second rock shaft, a lever carrying a rod over which the cloth is fed from the sinkers to the take-up roll, an arm on said first mentioned rock shaft, and a link between said arm and said lever which carries said rod by virtue of which the let-out and take-up of cloth between

sinkers and cloth take-up roll will be coordinated with the sinker and needle movements that are due to the rock-shaft-rocking movements.

56. The machine of claim 11 wherein said means for reciprocating said needle-bar-carrying shafts includes an eccentric drive and said rock-shaft-rocking means includes a double eccentric drive.

57. The machine of claim 11 wherein the needle-bar-carrying shaft-bearings are offset with respect to the axis of the rock shaft and wherein said means for reciprocating said needle-bar-carrying shafts includes an eccentric drive and said rock-shaft-rocking means includes a double eccentric drive.

58. In a knitting machine wherein thread guides, sinkers, hook knitting needles and hook closers are employed, the improvement which includes: a shaft; a bracket pivotally-adjustably mounted on said shaft and having a bearing transversely of the shaft; a sinker-bar-carrying shaft longitudinally movable in said bearing; a sinker bar on said sinker-bar-carrying shaft; sinkers on said sinker bar; means to reciprocate said sinker-bar-carrying shaft to advance and retract said sinkers; and means for adjusting the position of said bracket about said first mentioned shaft.

59. In a knitting machine employing thread guides and means for racking the same; a rock shaft; a needle bar carried by said rock shaft; a tongue bar carried by said rock shaft; a sinker bar carried by said rock shaft; hook needles on said needle bar; hook-closing tongues operatively connected to said tongue bar; sinkers on said sinker bar; means for imparting movements to said needle bar to effect reciprocation of said needles in their lengthwise direction; means for imparting movements to said sinker bar to move the sinkers forwardly and backwardly; means for actuating said tongue bar to cause the tongues to close and open the needle hooks; means for rocking said rock shaft to impart an arcuate movement to said needles and tongues; the afore-

said movement-imparting means being cooperatively connected together to cause said needles, said tongues, and said sinkers to perform, with said thread guides, knitting operations; and means to mount said sinker bar operatively angularly adjustably on said rock shaft.

60. In a knitting machine which employs a supporting frame, sinkers, thread guides, hook needles, and needle-hook closers, the improvement which includes: a suitably supported rock shaft; means for rocking said shaft; needle-bar-carrying shaft-bearings secured to said rock shaft; needle-bar-carrying shafts mounted to reciprocate in said needle-bar-carrying shaft-bearings; a needle bar secured to said needle-bar-carrying shafts; brackets pivotally-adjustably mounted on said rock shaft; sinker-bar-carrying shafts mounted in said brackets; a sinker bar secured to said sinker-bar-carrying shafts; means adjustably holding said brackets stationary; and means operable in harmony with the rocking of said rock-shaft for effecting the movements of said needles, said needle-hook closers and said sinkers to perform knitting operations.
